UNITED STATES PATENT OFFICE.

CHARLES H. HAUPT, OF ELIZABETH, NEW JERSEY, ASSIGNOR TO STANDARD DEVELOPMENT COMPANY, A CORPORATION OF DELAWARE.

TANK CONSTRUCTION.

Application filed August 14, 1922. Serial No. 581,756.

The present invention relates to improvements in oil storage tanks and will be fully understood from the following description thereof, illustrated by the accompanying drawings, in which:

Fig. 1 is a plan view of the tank;

Fig. 2 is a sectional view centrally through the tank;

Fig. 3 is a horizontal sectional view through the tank below its top, showing the floating roof of the tank in plan;

Fig. 4 is a detailed sectional view taken through the center of the tank on a horizontal plane;

Fig. 5 is a vertical detailed sectional view taken at right angles to the plane of section of Fig. 4;

Fig. 6 is a horizontal sectional view through the tank below its top, showing a modified form of floating roof in plan;

Fig. 7 is a detailed horizontal sectional view through the center of the tank; and

Fig. 8 is a detailed vertical sectional view through the center of the tank at right angles to the plane of section of Fig. 7.

Referring more particularly to the drawings, the numeral 10 indicates the body of a tank, which may be, for example, cylindrical in form. A central post 11, which may likewise be cylindrical in form, rises from the center of the tank, its height being greater than the height of the walls of the tank. At the top of the central post 11 is mounted a plate 12 of substantially circular form, which serves as a central support for a plurality of radial, downwardly inclined beams or rafters 13 which serve to support the ledge roof 14. At their outer ends the beams 13 are supported by uprights 15 extending upwardly from the wall of the tank 10, so that the beams 13 are spaced above the latter. The ledge-roof 14 is conical in form, preferably with a low pitch, and the central portion thereof is cut away, as shown by the lines 16 on Fig. 1. The roof 14 hence is a ledge covering only the outer portion of the tank, overhanging the wall and spaced above it.

Within the tank is provided a float of sectional construction, the assembled sections

thereof forming a floating body of configuration similar to the section of the tank. The individual sections of the float are designated by the numeral 17 and, in the embodiment illustrated, are formed as circular 55 quadrant pans with upturned sides 18. At their centers, where they approach the central post 11, the pan sections 17 are formed to provide a re-entrant angle 19, which in the form illustrated is approximately a 90° 60 angle. As a result of the formation of these re-entrant angles at the centers of the float sections, a polygonal opening is formed centrally of the tank between the float sections and the central post 11 extends through this 65 opening.

Means are provided for holding the pans in their proper spaced relation with respect to the central post. This means may suitably be a frame 20 formed with depending 70 spaced legs 21 which are respectively secured to aligned sides of the re-entrant angles formed in adjacent float pans. Each of the frames 20 is likewise provided with horizontally extending frame members 22, between 75 which is mounted a roller 23. Each frame 20 hence serves both to hold two adjacent float sections together and to keep them properly spaced from the central post. The sections may also be bolted or welded together where 80 they meet, if desired.

Evaporation of stored liquids from the annular space within the tank surrounding the float sections and from the polygonal space at the center of the tank between the 85 float sections and around the central post is prevented by providing in these spaces a covering of suitable filler material, such as stable foam, for example, that described in the patent of Howard, Jennings and Kent, 90 No. 1,443,538, granted January 30, 1923.

Rain water or any other liquid accumulated within the pans 17 forming the floating roof of the tank may be removed by any suitable means, for example, by siphoning or draining to a point outside the tank. As such means do not form a part of the present invention, no showing thereof is made in the drawings.

Any suitable means, such as is well known 100

in the art, may be employed for filling and for draining the contents of the tank proper.

Figs. 6, 7, and 8, illustrate a modified form of floating roof construction which may be employed in connection with the present invention. In this form of construction the roof is formed in four sections 17^a illustrated as quadrants, the inner angles being cut off at 19^a to form a central square opening 10 surrounding the center post 11^a. The tank is indicated by numeral 10^a. The roof sections 17^a are secured together by any suitable means, for example, by bolts, by welding, or the like. To each of the sides 19^a forming the central opening, a vertical member 20^a is secured, this member having its top 21^a bent or turned over toward the central post 11^a. The members 20^a thus serve as guides in the upward movement of the floating roofs. As above described, the central opening and the space surrounding the floating roof are filled with any suitable material, for example, the stable foam above referred to.

25 I claim:

1. In combination, a tank, a float within the tank, said float being spaced from the walls of the tank, and a stable fluent foam filling the space between said float and the 30 wall of the tank and adapted to float upon the surface of the liquid in the tank.

2. In combination, a tank, a float within the tank, said float being spaced from the walls of the tank and being provided with 35 a central opening, and a stable fluent foam adapted to float upon the surface of the liquid in the tank and filling the space between said float and the wall of the tank and also filling the central opening in the float.

40 3. In combination, a tank, a float within the tank, said float being spaced from the walls of the tank and being provided with a central opening, a stable fluent foam adapted to float upon the surface of the liquid in the tank and filling the space between said float and the wall of the tank and also filling the central opening in the float and a 45 roof mounted upon said tank and spaced thereabove, said roof overhanging the walls 50 of said tank.

4. A tank, a float within said tank, said float being formed of a plurality of pan sections and said pan sections being formed to provide a central opening in the float and a 55 marginal opening between the float and the walls of the tank, and means for holding adjacent pan sections of said float together.

5. A tank, a float within said tank, said float being formed of a plurality of pan sections and said pan sections being formed to provide a central opening in the float and a 60 marginal opening between the float and the walls of the tank, means for holding adjacent pan sections of said float together and

for holding them in proper spaced relation 65 and a fluent filler between the float and the walls of the tank and in the central opening of said float.

6. A tank provided with a central upright post, a float in said tank, said float 70 being formed of a plurality of quadrant sections, each of which is provided with a reentrant angle whereby a central opening is formed about said central post, and spacing means comprising a frame having legs 75 depending into and secured to adjacent pan sections of said float and means supported by said spacing frames for holding said pan sections in proper relation to the central post.

7. A tank provided with a central upright post, a float in said tank, said float being formed of a plurality of quadrant sections, each of which is provided with a reentrant angle whereby a central opening is 85 formed about said central post, and spacing means comprising a frame having legs depending into and secured to adjacent pan sections of said float, means supported by 90 said spacing frames for holding said pan sections in proper relation to the central post and a floating filler between the float and the walls of the tank and in the central opening of the float.

8. A tank provided with a central upright post, a float in said tank, said float being formed of a plurality of quadrant sections, each of which is provided with a reentrant angle whereby a central opening is 95 formed about said central post, and spacing means comprising a frame having legs depending into and secured to adjacent pan sections of said float, means supported by 100 said spacing frames for holding said pan sections in proper relation to the central post, a stable foam filling between the float and the walls of the tank and in the central opening of the float and a roof mounted on 105 said tank and spaced thereabove, said roof overhanging the walls of the tank.

9. A tank provided with a central upright post, a float in said tank, said float being formed of a plurality of pan sections secured together and said pan sections being 115 formed to provide a central opening in the float, and spacing means secured to the sides of said pan sections forming the central opening for holding the float in proper relation to the central post.

10. A tank provided with a central upright post, a float in said tank, said float being formed of a plurality of pan sections secured together and said pan sections being formed to provide a central opening in the float, vertical uprights secured to the 120 sides of said pan sections forming the central opening, the upper ends of said uprights being turned inwardly toward the 125

central post, said vertical uprights thereby serving as spacing means for holding the pan sections in proper relation to the central post.

5 11. A liquid storage apparatus, comprising a tank that is adapted to hold liquid, a floating deck or roof that covers the major

portion of the surface of the body of liquid in the tank, and a sealing means consisting of a foamy, frothy substance floating upon the surface of the liquid in the tank between the side wall of the tank and the peripheral edge of said deck. ¹⁰

CHARLES H. HAUPT.
